UNITED STATES PATENT OFFICE.

JOHN M. McDONALD, OF DUBUQUE, IOWA, ASSIGNOR TO A. Y. McDONALD M'F'G. CO.,
OF DUBUQUE, IOWA, A CORPORATION OF IOWA.

VALVE-LOCK.

1,349,139.

Specification of Letters Patent. Patented Aug. 10, 1920.

Application filed December 30, 1918. Serial No. 268,874.

To all whom it may concern:

Be it known that I, JOHN M. McDONALD, a citizen of the United States, residing at Dubuque, county of Dubuque and State of 5 Iowa, have invented certain new and useful Improvements in Valve-Locks, of which the following is a specification.

The present invention has to do with an improved form of valve lock for locking 10 globe valves, gate valves, and the like, so that they cannot be opened or closed, except with the use of the appropriate key.

One of the objects of the invention is to provide a very simple form of lock of such 15 construction that it can be very readily and easily applied or removed, and of a form which, when applied, will absolutely and positively lock the valve, so that it cannot be either opened or closed. The device is so 20 constructed as to permit the use of a padlock of ordinary type, and the locking pin is so proportioned and mounted with respect to the valve casing that the padlock may be inserted with the parts in either 25 locking or unlocking position, so that neither the pin or padlock will be lost or misplaced.

Other objects of the invention will appear from a detailed description of the 30 same which consists in the features of construction and combinations of parts herein-after described and claimed.

In the drawing:

Figure 1 is a side elevation of a valve 35 showing the features of the present invention;

Fig. 2 is a front elevation of the same; and

Fig. 3 is a transverse section taken on line 40 3—3 of Fig. 1.

In the several figures the neck of the valve and the hand wheel for operating the same are designated by the numerals 3 and 4 respectively. The neck of the valve is enlarged at its base 5 which is of hexagonal 45 shape and merges into a cap plate 6 which is appropriately formed to connect in any approved manner with the body 7 of the valve. The neck 3 is provided with 50 standing upper and lower guide lugs 8 and 9 respectively, which are arranged in spaced relation and project from the neck at points immediately above and in line with the center one of the flat faces of the base; that is,

substantially perpendicular to the plane of 55 one of the sides of the base.

Each of the guide lugs is provided with a guide hole, the two holes being in alined relation. The guide holes afford a guideway for a locking pin 10 so mounted that 60 when in lowered position it will lie in adjacent relation to the underlying base side and rest upon the upper surface of the cap plate 6. This construction is not only compact but allows the cap plate to function as 65 a stop for the pin when moved in one direction. When in its elevated position, the upper end of the locking pin will project above the plane of the spokes 11 of the hand wheel and lie intermediate a pair of such 70 spokes, and at the same time the lower end of the locking pin will lie below the plane of the lower guide lug, so that, whether in raised or lowered position, the guide pin will always be held and guided by both of 75 the lugs which insure against removal of the pin by bending, or by otherwise tampering with the lock. The locking pin is provided near its lower end with a transverse hole 12 which is of a size to receive the 80 usual locking loop 13 of the padlock 14. The spokes of the hand wheel are less in thickness than the rim, so that the latter will stand above and below the plane of the 85 ribs. The parts are proportioned and arranged so that, when the locking pin is in lowered position, its upper end will lie within the plane of the rim while at the same time below the plane of the spokes, thereby effectually guarding the upper end 90 of the locking pin against unauthorized tampering.

The hole for the insertion of the padlock and the spacing of the guide lugs are so disposed that, when the loop of the padlock is 95 inserted with the pin in elevated or locking position, the upward movement of the pin will be so restricted or limited by contact of the loop with the lower face of the upper guide lug that it will be impossible to lift 100 the pin sufficiently to clear the lower guide lug, while at the same time the hole for the padlock is so disposed and arranged that with the pin in lowered or unlocking position and with its lower end resting upon the cap plate, it will be possible to insert the padlock in position at a point immediately below 105 the lower guide lug, thereby preventing re-

moval of either the pin or padlock and holding the latter with its upper end housed within the plane of the rim of the hand wheel.

5. The arrangement is an extremely simple one and at the same time the proportioning and spacing of the several parts is such as to insure sufficient strength and rigidity to prevent tampering. By employing the locking pin of the character described, and by using the padlock to hold the pin in the desired position of adjustment, rather than to make direct connection with the hand wheel, it is possible to use a padlock having a relatively small loop which would not be the case if the padlock were employed to make direct connection with the hand wheel itself.

I claim:

1. In combination with a valve casing having a neck enlarged at its base to provide a polygon with flat faces, a hand wheel projecting from the outer end of the neck, a guide lug outstanding from the neck at a point in alinement with one of the flat faces of the polygonal base, a locking pin slidably mounted within the guide lug in adjacent relation to said flat face of the base and adapted when projected to have its acting end brought into locking relation with the hand wheel, said pin being provided with a transverse hole, and a padlock having a loop adapted to be entered through the hole either

when the pin is adjusted to bring the hole above or below the guide lug, substantially as described.

35

2. In combination with a valve casing having a hand wheel, neck, and a base, a guide lug extended from the neck at right angles thereto, and provided with a hole therein, and a locking pin slidable through the hole of the lug and adapted to coöperate with the hand wheel to lock the same against rotation, the base of the valve casing being constructed to provide a clearance for the lower end of the pin, said pin having a transverse hole through which a padlock may be entered to hold the pin in either locking or unlocking position relative to the hand wheel.

40

3. In combination with a valve casing having a hand wheel, neck, and a base, a plurality of guide lugs extended from the neck at right angles thereto, and provided with holes therein, and a locking pin slidable through the holes in the lugs, and adapted to coöperate with the hand wheel to lock the same against rotation, the base of the valve casing being constructed to provide a clearance for the lower end of the pin, said pin having a transverse hole through which a padlock may be entered to hold the pin in either locking or unlocking position relative to the hand wheel.
